UNITED STATES PATENT OFFICE

2,549,451

REVOLVING DOOR DRIVING MEANS

Clement Elphick Gossling, Winnipeg, Manitoba,
Canada, assignor to Hudson's Bay Company,
London, England, a corporation of England

Application January 7, 1949, Serial No. 69,775
In Canada April 1, 1948

3 Claims. (Cl. 268—73)

1

This invention relates to revolving doors and more particularly to doors of the type in which manually operable driving means are provided whereby the user is relieved of the need of exerting the physical strength required to revolve the door.

A number of doors of this type have been proposed in which an electric motor is provided for driving the door, the motor being started and stopped by the user by means of manually operable switches provided on the door wings.

The object of the present invention is to provide an improved revolving door of great simplicity and reliability and with this end in view it comprises a continuously rotating driving element and manually operable clutching means for establishing a driving connection between the door and the driving element when desired.

The invention consists in the construction, combination and arrangement of parts hereinafter described and more particularly pointed out in the appended claims.

Referring now to the accompanying drawings which illustrate, by way of example, one convenient embodiment of the invention:

Figure 1 is a vertical elevation, partly in section of a revolving door equipped according to the present invention.

Figure 2 is an enlarged sectional elevation of the lower part of one of the door wings, on the line 2—2 of Figure 5.

Figure 3 is a section on line 3—3 of Figure 1, Figure 4 is a section on line 4—4 of Figure 1, Figure 5 is a section on line 5—5 of Figure 2, Figure 6 is a section on line 6—6 of Figure 2, and

Figure 7 is an enlarged section of a form of reduction gearing through which the door is driven.

The invention may be applied to any form of revolving door, the principal elements of which are indicated, more or less diagrammatically, in Figure 1 in which 1 indicates the usual vertical shaft, 2 indicates one of the lateral enclosure panels, 3 the ceiling panel, 4 indicates two of the radial door wings and 5 the floor level.

According to the illustrated form of the present invention the floor beneath the door is formed with a recess or pit 6 to accommodate a prime mover, preferably in the form of an electric motor 7, the shaft of which is connected, through an intermediate shaft 8 and couplings 9, with a high speed shaft 10 of a reduction gearing indicated generally at 11 in Figure 1 and also accommodated in the recess 6.

2

A convenient form of gearing is shown on a larger scale in Figure 7. This gearing comprises a casing 12 having a flange 13 the top surface of which is disposed flush with the floor level 5. 5 The inner end of the shaft 10 carries a small gear 14 meshing with a larger gear 15 carried by a shaft 16 which also carries on its upper end a small gear 17 in mesh with a large ring gear 18 secured to a circular plate 19 formed with a central boss or sleeve 20. At the centre of the casing 12 there is provided a bearing sleeve 21 into which fits the lower end of the central door shaft or spindle 1. The lower end of the shaft 1 may be formed with a vertical slot as at 22, the slot being detachably engaged by a key or projection 23 carried by the sleeve 21 to support the shaft 1.

Suitable anti-friction bearings 24 are preferably provided between the boss 20 and the central sleeve 21, and anti-friction means may be provided as at 25 and 26 for the shafts 10 and 16 respectively.

The upper surface of the plate 19 is disposed flush with the floor level 5 and a ring-shaped plate 27 is secured in a recess in the plate 19 to prevent entry of foreign matter into the central bearings 24. A larger ring-shaped plate 28 is secured in a recess in the flange 13 of the casing 12, this plate being wide enough to extend into an annular recess 29 in the upper surface of the plate 19. Suitable sealing means are preferably provided for preventing entry of dirt through the space between the periphery of the plate 19 and the gear casing 12 and for preventing the exit of lubricating oil from the casing. These sealing means may take the form of a ring of felt or similar material 30 arranged in an annular recess 31 in the plate 19, the felt ring being pressed constantly into contact with the under surface of the plate 28 by means of compression spring 32 bearing on a metal ring 33 which in turn bears against the bottom of the felt ring.

The operating mechanism carried by each wing 4 of the door will now be described. This mechanism comprises a hand bar 34 which, in the form shown, extends across almost the entire width of the door wing 4, though a shorter bar may be used if desired. The bar 34 is keyed or otherwise secured to a horizontal rod or shaft 35 which is rotatably mounted in bearings 36 carried by brackets 37 fastened to the appropriate side of the door wing 4. The hand bar may be formed with enlargements 38 in the upper parts of which the bearings 36 are accommodated. These bear-

ings therefore prevent longitudinal movement of the bar 34.

Rigidly secured to the outer end of the rod 35 is a crank-like member 39 the free end of which preferably has a curved surface, as at 40, concentric with the axis of the rod 35. The crank 39 projects into a recess 41 in the door wing. Secured to the top of the crank 39 is one end of a flexible, inextensible tension member such as a cable 42 which passes down through a passage or bore 43 in the door wing. A suitably shaped cover member 44 is preferably provided over the crank 39 and secured to the door wing as by means of studs or bolts 45. A similar member 44 may be provided adjacent the other end of the hand bar 34 if desired.

The passage 43 extends to a point near the bottom of the door wing and there communicates with a horizontal passageway 46 which in turn communicates with a recess 47 arranged over the plate 19 of the driving mechanism. A pulley 48 is provided adjacent the junction of the passages 43 and 46. The cable 42 passes around the pulley 48 and extends along the passage 46 to a point near the recess 47 where it is attached to a connector member 49. A spring 50 is compressed between the member 49 and a stop plate 51 which is formed with a slot 52 to accommodate the cable 42 and secured to the door wing by screws 53. The door wing is suitably recessed to receive the plate 51 and provided with the customary metal kick plates 54.

It will be seen that the driving plate 19 is of sufficiently small diameter that users do not need to step on it in passing through the door.

A movable clutch element 55 is provided with a facing of friction material such as brake lining 56 and a vertical web 57 projecting upwardly into the recess 47 in the door wing, the upper edge of this web being formed with inclined surfaces 58. The clutch element 55 is preferably provided with means to urge it upwardly, a leaf spring 59 being shown for this purpose, this spring being secured at one end to the clutch element and at the other to the bottom of the door wing at 60.

A stationary plate 61 similar in shape to the web 57 but with reversely disposed inclined surfaces 58 is provided at the top of the recess 47 in the same vertical plane as the web 57. The web 57 and plate 61 lie between metal plates 62 formed with openings 63. Pairs of rollers 64 are rotatably mounted on shafts 65 journaled in parallel links 66 which are attached to the connector element 49 at 67. The rollers 64 are preferably flanged to prevent excessive lateral movement of the rollers with respect to the web 57 and plate 61, as is clearly shown in Figure 5.

The space over the motor 7 between the gear casing 18 and the floor 5 is covered by a floor plate 68.

A suitable stop, such as that shown at 69 in Figure 3, may be provided to limit the swinging movement of the bar 34 away from the door wing.

The operation of the invention is as follows: The parts are shown in their normal positions in the drawings and in this position the motor 7 rotates the driving plate 19 continuously through the gearing 11, but the door wings remain stationary since the spring 50 presses the rollers towards the widest part of the space between the inclined surface 58, so that the leaf spring 59 is free to lift the clutch element 55-56 out of engagement with the driving plate 19.

The spring 50 also exerts a constant downward pull on the crank element 39 (see Figure 3) and thus holds the lower part of the hand bar 34 away from the door wing 4, in which position the stop 69 engages the cover member 44.

When a person wishes to enter or leave the building he or she enters the door enclosure in the usual way and presses lightly on the lower part of the hand bar 34 (see arrow 10, Figure 3) causing the hand bar to swing towards the door wing. This movement causes the crank 39 to swing upwardly and exert a pull on the cable 42. This pull is transmitted to the rollers 64, causing them to ride along the inclined surfaces 58 against the action of spring 50. The clutch element 55-56 is thus thrust downwardly into frictional engagement with the constantly rotating driving plate 19. The door is therefore caused to revolve so long as the user presses on the hand bar 34 and thus maintains the clutching element in driving engagement with the plate 19. As soon as the door has revolved to the required extent the user releases the hand bar 34, the crank 39 descends, the spring 50 expands, the rollers 64 move down the inclines 58 and spring 59 raises the clutch element 55, thus de-clutching the door from the driving plate 19, so that the door remains stationary until another person wishes to enter or leave the building.

If the slope of the inclines 58 are suitably arranged the spring 50 need be of no very great strength and a considerable mechanical advantage can be obtained for actuating the clutch element, so that the operation of the hand bar 34 calls for only a minimum of exertion on the part of the person using the door. The bar can be easily actuated by the arm or elbow when the door is used by a person having both hands occupied in carrying parcels.

The foregoing description and accompanying drawings are given by way of example only and modifications may be resorted to in many ways within the scope of the appended claims.

What I claim is:

1. In combination with a revolving door, a driving means consisting of a prime mover, gearing, a plate driven by said prime mover through said gearing, and manually operable clutching means, consisting of a hand bar, a cranklike member and a flexible member connected to a clutch engaging means for establishing a driving connection between said door and said plate when desired, said plate being rotated continuously and wherein the clutch engaging means consists of a movable clutch element fixedly connected to a vertical web.

2. In combination with a revolving door, a driving means consisting of a prime mover, gearing, a plate driven by said prime mover through said gearing, and manually operable clutching means, consisting of a hand bar, a cranklike member and a flexible member connected to a clutch engaging means for establishing a driving connection between said door and said plate when desired, said plate being rotated continuously and wherein the clutch engaging means consists of a movable clutch element fixedly connected to a vertical web, said clutch element being engaged by rollers siding on an inclined plane.

3. In combination with a revolving door, a driving means consisting of a prime mover, gearing, a plate driven by said prime mover through said gearing, and manually operable clutching means, consisting of a hand bar, a cranklike member and a flexible member connected to a clutch en-

gaging means for establishing a driving connection between said door and said plate when desired, said plate being rotated continuously and wherein the clutch engaging means consists of a movable clutch element fixedly connected to a vertical web, said clutch element being engaged by rollers siding on an inclined plane, said rollers being acted upon by said flexible member connected to said hand bar, said clutch element being releasable by spring means.

CLEMENT ELPHICK GOSSLING.
